CONDIMENT DISPENSER

Raymond T. Killa, Thiensville, Wis.

Application November 27, 1945, Serial No. 631,066

6 Claims. (Cl. 65—45)

1

My invention relates to condiment dispensers and more particularly to a twin salt and pepper shaker such as is commonly employed in homes and restaurants.

The invention seeks among other objects to provide a device that is in reality a combined receptacle for two separate and distinct condiments.

Another object of my invention is to provide a device that will dispense but one of the two condiments at one time.

A still further object of my invention is to provide such a device that may be operated with ease, will not tip readily and is provided with a contour that enables it to be conveniently grasped by the user.

Still another object of my invention is to provide a device of the character described that may be readily filled and cleaned, one that will keep the dispensing apertures free of corrosion and congestion at all times.

Other and incidental objects not particularly mentioned in the foregoing will be apparent as the description proceeds when taken in conjunction with the drawings in which

Figure 1 is a perspective view of the device,

Figure 2 is a fragmentary perspective view of the inner valve arrangement of one of the cap members,

Figure 3 is a plan view of the valve arrangement in an open position inside of the cap showing the dispensing apertures exposed,

Figure 4 is a similar view as that shown in Figure 3 in which the dispensing apertures are closed by the semi-circular valve disc,

Figure 5 is a fragmentary cross-sectional view of the device taken at the line 5—5 of Figure 6,

Figure 6 is a cross-sectional view of the device taken at the line 6—6 in Figure 5,

Figure 7 is a fragmentary cross-sectional view of the upper portion of the device illustrating the manner in which the valve discs function, opening the apertures in the lower cap while the apertures in the upper cap are closed, and

Figure 8 is a cross-sectional view of the cap arrangement fitted to one of the spouts of the device and constructed in a manner to permit the cap engaging a bead forming an integral part of and extending outward from the surface of the spout.

Similar characters of reference indicate corresponding parts throughout the several views and referring now to the same the character 10 illustrates a body or receptacle wide at its extreme base 11 and terminating into two oppositely disposed elongated spouts 12 and 12'. The recep-

2

tacle 10 is separated on the inside by an angularly disposed partition 13 extending from the bottom of the receptacle to the dividing point 14 at its top.

The design and contour illustrated lends itself very readily to the article, for it provides a substantially firm base and a convenient shape to permit its being manipulated easily. However I do not wish to confine myself to the specific structure described and illustrated for many modifications may be made in the shape of the device without departing from the scope of the invention.

Both spouts 12 and 12' being open at their upper ends are provided with caps 15. These caps may be constructed of molded plastic material or of metal. They are shown arranged to fit snugly over the outer face of the spouts 12 and 12'. In Figure 8 is shown a modified form in which the spout 12 is provided with an outwardly extending bead 16 and the cap 15 is provided with a groove arrangement 17 to engage and fit over the bead 16.

Obviously the caps 15 shown in the illustration of square design may be made any shape depending on the shape of the spout 12 and 12'. Centrally disposed in the face of the cap 15 is a pin

25 18 acting as a bearing for a semi-circular valve disc 19 provided with a weighted portion 20 as shown. The pin 18 is longer than the thickness of the disc 19 thereby allowing the disc 19 to move freely toward and away from the inside surface 30 of the cap 15. Immediately around the pin 18 and in semi-radial alignment thereto are shown a plurality of perforations or apertures 21 in the face of the cap 15. These perforations are for the purpose of permitting the condiment within

35 the body 10 to be forced out by the conventional shaking method. The weighted portions 20 being heavier than the semi-circular valve disc portion 19 act as a pendulum and will always be suspended toward the bottom of the cap when the device is tilted, and as the perforations 21 are

40 disposed toward the lower part of the cap face when the device is set upright on its base 11, it will be manifest that when the device is tilted as is shown in Figure 7 the lower spout 12' will have the weighted portion 20 of the disc 19 downward thereby permitting the perforations 21 in the cap 15 on the spout 12' to be open while the perforations 21 in the cap 15 on the spout 12 at the top will be closed. This procedure permits condiments from the lower spout only to be expelled.

45 The disc 19 being permitted to revolve freely on the pin 18 and also being permitted to move forward and backward on said pin, will have a tendency to keep the inner face of the cap 15 clean and free from corrosion or congested par-

ticles of the contents, thereby permitting only the normal free particles from working their way through the perforations 21.

In the event that the device would be tilted entirely the valve discs weighted as they are would cause all perforations to be closed.

The caps 15 being made removable permit filling the receptacle through the oppositely disposed spouts. However if desired the caps 15 may be permanently attached, in which case separate 10 openings provided with closing means not shown, may be built into the base of the device for filling purpose.

The perforations 21 arranged in only one-half of the face of the cap 15 allow sufficient space 15 to permit conspicuous identification to be placed onto the outer face of the cap for the convenience of the user.

I have entered into a detailed description of the construction and relative arrangement of 20 parts embraced in the preferred embodiment of my invention in order to impart a full, clear and exact understanding of the said embodiments. I do not desire however to be understood as confining myself to the said specific construction and 25 relative arrangement of parts, as many changes and modifications may be made such as fall within the scope of the invention as defined by my appended claims.

Having thus described my invention, what I 30 claim and desire to secure by Letters Patent in the United States is:

1. A device of the character described comprising in combination a receptacle closed at its base, 35 said receptacle terminating into two spouts open at their upper ends, said spouts protruding outward from said receptacle in opposite relations to one another, a partition separating said receptacle into two separate compartments, each compartment terminating into one of said spouts, cap members disposed for contact with the open end of said spouts, said cap members provided with a semi-circular valve disc, a pin attached to said cap member providing a bearing for said disc, said disc equipped with a weighted portion heavier than the semi-circular portion of said disc, and perforations through a portion of the face of said cap for permitting the contents of said receptacle to be expelled.

2. A device as described in claim 1 in which 50 the pin is of greater length than the thickness of said valve disc thereby permitting longitudinal movement of said disc on said pin.

3. A device of the character described comprising in combination a receptacle, said receptacle opening into two oppositely disposed spouts at its upper end, a partition separating said receptacle into two compartments, each of said compartments terminating into one of said

spouts, cap members contacting the open end of said spouts, perforations through one-half of the surface of the face of said cap member, a pin attached to said cap member extending inward from said cap, a semi-circular valve disc provided with a weighted portion, said disc mounted onto said pin and permitted to revolve freely thereon and means for attaching said cap onto the open end of said spouts.

4. A device of the character described comprising in combination, a receptacle closed at its base, said base being of a wider diameter than the body of the receptacle, said receptacle terminating into two oppositely disposed spouts open at their upper ends, a partition separating said receptacle into separate compartments, each compartment terminating into one of said spouts, cap members disposed for engagement with the open end of said spouts, said cap members having perforations through one-half of the face of said cap, a pin disposed centrally within said cap and extending inward therefrom, a semi-circular valve disc pivotally mounted onto said pin, said valve disc provided with a weighted portion acting as a pendulum, said weighted portion of greater weight than the semi-circular disc and said pin being longer than the thickness of said valve disc to permit the sliding of said disc towards and away from the inside of said cap.

5. A device as described in claim 4 in which the wall of said base is provided with openings leading to the inner area of said compartments, and means for closing said openings to retain the condiment within said compartments after filling.

6. A cap to be used in combination with a condiment dispenser, said cap provided with a plurality of perforations radially spaced through one-half of its surface, a semi-circular valve disc rotatably mounted on a pin centrally disposed and extending inward from said cap, said pin of a length greater than the thickness of said valve disc, and a weighted pendulum integrally attached to said disc and disposed outwardly therefrom, causing the disc to be raised away from the perforation when the container is tipped.
